UNITED STATES PATENT OFFICE.

EZECHIEL WEINTRAUB, OF BOSTON, MASSACHUSETTS, ASSIGNOR TO SUBMARINE SIGNAL COMPANY, OF PORTLAND, MAINE, A CORPORATION OF MAINE.

METHOD OF CHANGING RESISTANCE IN A CIRCUIT AND APPARATUS THEREFOR.

1,244,150.

Specification of Letters Patent. Patented Oct. 23, 1917.

Application filed April 13, 1916. Serial No. 90,861.

To all whom it may concern:

Be it known that I, EZECHIEL WEINTRAUB, of Boston, in the county of Suffolk and State of Massachusetts, a citizen of the 5 United States, have invented a new and useful Improvement in Methods of Changing Resistance in a Circuit and Apparatus Therefor, of which the following is a specification.

10 The present invention is a new type of microphone capable of varying a much larger current than has been possible in the past, and of accomplishing this variation in better conformity to the sound variations 15 that are to be reproduced.

The important applications of this invention are in long distance telephony, wireless telephony, submarine signaling, and in all other cases where variation by means of 20 voice or sound in general of larger amounts of energy than heretofore possible is desired.

In a microphone the sound waves produced by the voice impinge upon a diaphragm and force it to move backward and forward in conformity with the impressed 25 sound waves. The diaphragm actuates one of the electrodes of an imperfect contact. The imperfect contact thus arranged is connected 30 in an electrical circuit and the movements of the diaphragm and the consequent movement of its associated electrode produce changes in the resistance of the circuit between this electrode and another or 35 other associated electrodes. The object in the design of a microphone is to produce changes in the resistance of an electrical circuit similar to the changes in the compressional air waves of the voice and to 40 make such changes in resistance take place through as wide a range as possible without making the resistance infinite, that is to say, without breaking the circuit at the point of contact.

45 In the past it has been usual to employ carbon for one or both of the electrodes of the imperfect contacts of microphones. Moreover, to prevent the circuit being broken at the electrodes by an excessive 50 movement of the associated receiving diaphragm, it has been usual, of late years to interpose finely divided particles of carbon between the front and back electrodes. The

use of finely divided or granular carbon has a still further advantage in that it affords 55 a large number of paths for the current passing between the front and the back electrodes. For a given current passing through the circuit this subdivision of the current in the microphone prevents such an 60 excess of current passing at any one point as will produce arcing at that point, with a consequent destruction of the surfaces of the electrodes and the production of foreign 65 disturbing noises known as "burning" or "hissing."

In designing a microphone, therefore, the object sought must be to so form the electrodes and current-varying medium that the current will be varied through the widest 70 possible range without burning and without the circuit ever becoming broken.

There is still another point to be considered. The heat at the small points of contact becomes considerable and the material 75 used for the electrodes must be such that the electrodes will not weld together and thereby prevent further changes of resistance.

In the present invention the range within 80 which changes in resistance can be effected has been increased by raising the electrodes or current-varying medium to a high temperature. It is known that the passage of current between electrodes is facilitated if 85 their temperature is raised. This is explained in modern theory by assuming emission of negatively charged corpuscles, so-called electrons. The hotter the electrodes the larger the number of these electrons, the 90 greater the current that can be carried, and the greater also the distance to which the electrodes can be separated without an actual break of circuit.

When carbon or similar material is used 95 it is necessary to avoid the presence of oxygen or oxidizing gases as these would cause rapid combustion at the elevated temperature used. The absence of oxygen is also instrumental in preventing "burning" 100 and "hissing." I have discovered that even traces of oxygen, water vapor, or other oxidizing gases, or, in general, of any gases which are capable of reacting on carbon are to be carefully eliminated.

105 The electrodes are therefore in the pres-

ent invention in an inert medium, free from such active gases. As such an inert medium I prefer to use either a vacuum or one of the rare gases especially argon.

5 At the temperature used in the present invention it becomes possible to utilize other substances than carbon, substances which hitherto have never been successfully employed as the current-varying media of microphones. Thus it is well known that 10 certain metallic oxides at high temperatures decrease in resistance and emit electrons at a rate exceeding that characteristic of metals or carbon, thereby making possible a larger 15 range of electrode movement without welding or breaking circuit.

Oxids have never before been found comparable with carbon as current-varying media. The reason for this has been due 20 partly to the high resistance usually inherent in such substances when cold but more especially to the fact that when cold electrons can not pass readily from the mass and as a consequence the range of movement of the 25 electrode without interruption to the circuit is extremely small. When heated to a high temperature both of these defects are eliminated.

In view of the above I have devised apparatus shown in the drawings in its preferred form, but not necessarily limited to the form there shown. In these drawings—

Figure 1 is a longitudinal section of apparatus embodying this invention;

35 Fig. 2 showing a modification thereof, and

Fig. 3 showing diagrammatically the electric circuits, etc., which may be used in carrying out my invention.

40 Fig. 4 shows a further modification described below, the spiral being in perspective and the casing in section.

1 is the metal diaphragm such as is usual in microphones and which is actuated by 45 compressional voice or other sound waves in the air. 2 is a rod attached to the diaphragm by a fastening means as at 6, and carrying the front electrode 4, which, however, may be integral with it. The rear 50 electrode 5 is attached preferably to the rod 3 and may be adjusted to and from the electrode 4 by means of the adjusting screw 7 to which the rod 3 is attached.

Concentric with the rods 2 and 3 is a 55 heater inclosing the electrodes 4 and 5. It may be variously constructed, but as shown it is electrical and consists of a highly refractory tube 8 about which is wrapped a spiral of resistance wire 9 outside of which 60 is a layer of insulating material 10. Surrounding the heater is a quartz tube 11 secured to metal ends 12 and 13 by which it is securely held in place, and the exterior may be water-cooled, if desired. In the metal 65 end 13 are insulating bushings 14, 16 and 17

and a metal tube 19. The terminals 15 and 18, to which are fastened the ends of the resistance wire 9, are made fast in the insulating bushings 14 and 17. The adjusting screw 7 which holds one end of the rod 3, 70 turns in the bushing 16. At the other end of the quartz tube is the metal end 12 in which is fastened the metal tube 20. The metal diaphragm 1 is clamped to the metal end 12 by means of the clamping ring 21, which 75 may carry the ordinary telephone mouth-piece 22. The joints in this device are all made gastight, and the tubes 19 and 20 should be connected either to an air pump so that the chamber within the heater may 80 be made a vacuum chamber, or else to a reservoir of inert gas by which the chamber may be filled.

In the modification shown in Fig. 2, the electrodes 4 and 5 are differently shaped and 85 do not touch, but the end of one of them is formed to contain granules of electrode material, for example, carbon, or for high resistance microphone metallic oxides, and the end of the other is constructed to hold these 90 granules in place; the two forming a box or casing for the granules which make contact between both rods.

In Fig. 3 there is shown the preferred arrangement of circuits in which the heater 24 95 is energized by the battery 25, or any other source of current. The current between the electrodes 4 and 5 is energized by the battery 27 for which the rods 2 and 3 serve as conductors to the electrodes. Variations of this 100 latter current are caused by microphonic action at the electrodes 4 and 5 and are transformed by the transformer 26 to a secondary current 28.

Referring to Fig. 1, it is evident that if 105 the rods 2 and 3 are made of such small section that little heat may be conducted by them, the electrodes 4 and 5 may be heated to a temperature sufficiently high by means 110 of the current passing between them, but under ordinary conditions the separate heater is desirable. Their length is immaterial so long as they furnish means of supporting the electrodes under the required 115 conditions of heat.

In Fig. 4 I have shown another form of 120 my invention in which one of the electrodes 30 is formed as a spiral and is heated to the high temperature required by an auxiliary current passing through it. In this view 125 the diaphragm 1 has attached to it a rod 31, perpendicular to the plane of the spiral, the end of which rod terminates in the center of the spiral 30. The rod is connected with a battery 32 and a receiver 33 by the wires 130 34, one of which is connected to the spiral 30. The heating circuit comprises the wire 35, battery or other source of current 36 and the connection between 36 and the spiral 30. The whole is inclosed in an airtight casing 130.

37 of which the diaphragm 1 is one wall. 38
is a mouthpiece leading to the diaphragm.

The combination of the extremely heated
5 electrode in a medium entirely freed from
oxygen produces a transmitter of great
power, one which is free from foreign dis-
turbances, and is capable of varying cur-
rents never before used in telephone trans-
mitters.

10 Other forms falling within the scope of
my invention will suggest themselves to
those skilled in the art, my invention con-
sisting in maintaining one or both electrodes
at a high temperature.

15 What I claim as my invention is:

1. That method of changing resistance in
a microphonic circuit which consists in heat-
ing one or both of the electrodes of the mi-
crophone to a temperature above that of
20 initial incandescence and causing the ap-
proach and retraction of said electrodes.

2. That method of changing resistance in
a microphonic circuit which consists in heat-
ing one or both of the electrodes of the mi-
crophone in the presence of an inert gas to
25 a temperature above that of initial incan-
descence and causing the approach and re-
traction of said electrodes.

3. A microphone and means for maintain-
30 ing the microphonic contacts thereof at a
temperature above initial incandescence in
an atmosphere freed from oxygen.

4. A microphone inclosed in an atmos-
phere of one of the chemically inert gases

and means for maintaining the microphonic 35
contacts thereof at a temperature above
initial incandescence.

5. A means for changing resistance in a
circuit comprising two electrodes of which
one or both are movable, a granular ma- 40
terial between them, and means to maintain
the whole at a temperature above initial in-
candescence.

6. A microphone comprising electrodes
located in an exhausted space and main- 45
tained at a temperature above initial in-
candescence and means for maintaining said
electrodes at such temperature.

7. A microphone comprising two elec-
trodes one or both of which are movable and 50
separated by material such as oxids, nitrids
or the like, which become conductive at a
temperature above initial incandescence, and
means for maintaining them at such tem-
perature.

8. That method of changing resistance in
a microphonic circuit which consists in heat-
ing one or both of the electrodes of the mi-
crophone to a temperature at which ther- 60
mionic emission is effected and causing the
approach and retraction of said electrodes.

9. A microphone inclosed in an atmos-
phere of one of the chemically inert gases,
and means for maintaining the microphonic
contacts at a temperature at which ther- 65
mionic emission is effective.

EZECHIEL WEINTRAUB.
